UNITED STATES PATENT OFFICE

HARRY D. GABER, OF CLEVELAND, OHIO

JAIL-DOOR-LOCKING MECHANISM

Application filed June 20, 1927. Serial No. 200,087.

This invention relates to mechanism for locking jail doors and is of the type in which a row or bank of jail doors is controlled by mechanism located outside of the jail corridor with which all of the cells communicate. Mechanisms of this general type are well known in the art, the object of the present invention being to simplify and improve upon the apparatus by which the jail doors are locked.

In the modern jails where the cells are arranged in banks, and it is necessary to provide mechanism by which all of the cells in a bank can be opened or closed simultaneously by the guards at a point outside of the prisoners' corridor, it is also necessary to lock the cell doors open, and to provide means by which the individual cell doors can be opened or closed without affecting the other cell doors in the banks. All of these functions can be performed by the mechanism here shown and described, which is an improvement upon previous constructions of this type on account of its simplicity.

In the drawings, the preferred form of the invention is shown, it being understood that the details of construction need not necessarily be followed, as variations and changes may be made within the scope of the invention without departing from the essential features thereof.

In the drawings,

Figure 1 is a front elevation of one end of a row or bank of cells, the mechanism being duplicated along the entire bank, the view here being taken at the end of the row where the control mechanism is located;

Figure 2 is an end view showing the control mechanism;

Figure 3 is an enlarged view of the lock bolt for a jail door, being a section taken on the line 3—3 of Figure 4;

Figure 4 is a plan view of the parts shown in Figure 3;

Figure 5 is a section on the line 5—5 of Figure 1;

Figure 6 is a section on the line 6—6 of Figure 1;

Figure 7 is a section on the line 7—7 of Figure 1;

Figure 8 is an enlarged view at right hand end of a single cell showing the mechanism for locking the cells open; and

Figure 9 is a view showing a modification by which an individual cell can be controlled by a key.

Referring to Figure 1, the jail enclosure is indicated by the numeral 1, and the partition between adjacent cells by the numeral 2. The sliding door which ordinarily communicates with the prisoners' corridor is indicated at 3 and the control box located outside of the corridor, at 4. The track box which extends over the row of cells is indicated at 5 being enclosed on all sides except along the bottom of the box where it is provided with a slot 6 through which extend the door hangers 7. The hangers are formed with angular bends as shown in Figures 5 and 6 for the reception of a baffle plate 8 which is attached to the bottom of the track box and extends over the slot 6, thereby preventing tampering with the track box mechanism from below the slot. The upper edges of the door are protected and guided by angle iron rails 9.

Within the track box over each cell is located a horizontal track 10 having a groove 11 therein over the door, in which trackway run the ribbed door supporting rollers 12. The hangers 7 are formed upon and depend from a carriage 14 the extremities of which are forked to receive the rollers 12 mounted upon bearing pins 15. In order to prevent the door being lifted off the trackway, a depending angular bracket 16 is attached to the carriage at each roller and extends below and beneath the track 10.

The forward or left hand end of each carriage is provided with a depending hook 18 which constitutes a lock for holding the door in closed position, in cooperation with a pivoted catch or lock bolt 20. This lock bolt is shown in Figure 3, being pivoted on a pin 21 located in flanges 22 extending from a plate 23 secured to the bottom of the track box at the side of each cell. The lock bolt is yieldingly maintained with the catch elevated by a spring 24 attached to the lock bolt and to the top of the track box. The tail 29 of the

lock bolt is offset and to a pin 29^a on the tail is attached a flexible connection or chain 25 by which the lock bolt may be operated, the chain passing over a series of pulleys 26 to the 5 control box, where the end of each chain is attached to a pivoted control lever 28. It will be understood that there is a separate connection and control lever for each cell, all of which are brought together in the control 10 box, the chains passing through the track box and being mounted and guided therein, two chains only being shown in Figure 1. Each chain may comprise rigid sections if desired.

It will be observed that there are three 15 positions of the lock bolt shown in Figure 3 and indicated as A B and C positions; A being the locked position, B the unlocked position and C the locked open position, the control levers having corresponding positions in the control 20 box so that the condition of each cell will be apparent from an inspection of the control box.

With each door is associated a spring 25 plunger which opens the door when the lock bolt is moved from A position. The plunger is indicated at 30 being slidably mounted in lugs 31 formed upon the plate 23 and being urged to the left by a coil spring 32 bearing against one of the lugs 31 and confined by an 30 adjustable collar 33 on the plunger. The plunger is in alignment with a pin 35 adjustably mounted on the angular portion of the bracket 7. The end of the plunger remote 35 from the door is formed with a squared head 36 which slides upon the plate 23 to prevent the plunger from rotation. The tail 29 of the lock bolt is offset as has been described and extends over the plunger, resting upon a pad 38 on the plate 23. The tail of the lock bolt is 40 located in the path of the plunger head 36 when the door is closed, but when the door is opened and the plunger advanced, the tail of the lock will rest upon the head of the plunger, preventing movement of the lock bolt into 45 locked position until the door is closed.

Each carriage 14 has secured thereto near its right hand end a vertical guide bracket 40 in which is mounted a sliding latch bolt 41 the upper end of which is forked and provided with a roller 42 by which the latch bolt 45 is suspended from a horizontal lifting bar 44. The bar 44 is carried at its right hand end by a pivoted link 45 pivoted on a hanger 46 suspended from the top of the track box, and at 55 its left hand end by a bell crank lever 48 pivoted on a similar hanger 49. It will be noted that the extreme left hand end of the bar 44 is somewhat higher than the right hand end, the two levels being connected by the inclined 60 surface 50 so that as the door is brought to closed position the latch bolt is elevated slightly.

The bell crank 48 is connected by an adjustable link 51 with the forward end of the 65 lock bolt, so that as the lock bolt is moved

from locking position, the lifting bar 44 will be raised. On the hanger 46 is secured a keeper or detent 52 having a notch 53 on its under surface with which the bolt 41 aligns when the door is fully opened. By moving 70 the lock bolt to its C position the lifting bar 44 is raised until the upper end of the latch bolt engages the notch 53 thereby locking the door in open position.

The end of the latch bolt is directly over the pull bar by which the cell doors are closed. This pull bar is indicated by the numeral 55 and extends the entire length of the bank of cells. The pull bar is made in sections 55^a each section being screw-threaded and received in screw-threaded recesses in a block or gap nut 56 at each cell, the gap nut being in register with the latch bolt when the door is closed, and the pull bar drawn forward. The upper side of each gap nut is formed with a recess 57 to receive the latch bolt, the right hand wall of the recess being higher than the left hand wall as shown in Figure 8. The gap nuts are provided with bearing pins 58 for rollers 59 which travel in a trackway 90 60, preferably forward as a part of the baffle 8. The pull bar extends toward the control box, being secured at that end to a roller supported rack 62, this rack being engaged by a floating pinion 63 which also engages a 95 stationary rack 64 secured to the top of the track box. The pinion 63 is carried upon the forked end of a link 65 pivoted to a crank 66 carried by a pinion 67 mounted in a bracket 68 in the upper portion of the control box. A vertically movable rack 69 engaging the 100 pinion 67 is mounted in the control box being moved by a pinion 70, supported in brackets 72 and actuated by a handle 73 which is held in closed position by a keeper 75. The 105 mechanism which has just been described, constitutes means for multiplying the movement transmitted by the handle 73.

The operation of the mechanism which has been explained is as follows:

When the cell doors are closed, each door is securely locked by means of the lock bolt 20 and the latch bolt 41 which latter prevents the opening of the door by reason of its engagement with the gap nut 56. This gives a 115 double lock on the cell door and effectually prevents any opening of the door. It will be noted that all of the locking mechanism is contained within the track box above the cell so that tampering with the locks is effectually 120 prevented. When the cells are to be opened, one or all of the levers 28 are lowered from their raised or locked position A to the intermediate or unlocked position B which moves the lock bolt to its B position, releasing the catch 18, and the spring plunger gives the door impetus sufficient to send it to the end of its travel which may be limited in any suitable manner, preferably by the end of the slot 6, so that the bolt 41 is in register with 125 130

the notch 53. If the doors are to be locked open, the selected levers 28 are moved to their lowermost position which moves the lock bolt to its C position, which through the connecting link 51 elevates the latch bolt until it is received in the keeper 52. When any of the doors are to be closed, the appropriate lever or levers 28 are raised which lowers the latch bolt into engagement with the gap nut, and then the pull bar is moved forwardly which moves the door to closed position where it is engaged by the lock bolt. It will be observed that when the bar 44 is lowered, it operates as a positive mechanical means for moving the latch bolt into engagement with the gap nut. Heretofore gravity has been relied upon to cause the latch bolt to engage the gap nut, and the present device is an improvement in this respect. Before the door reaches its locked position the latch bolt is fully engaged in the recess in the gap nut and the doors can be moved either way by the pull bar. As the door reaches its closed position, the roller 41 rides up along the incline 50 so that the lower end of the bolt 41 clears the lower wall of the gap nut. This enables the pull bar to move toward the left after the door is closed so that other doors may be picked up by the pull bar.

In the modification shown in Figure 9, additional means are provided by which the individual doors may be opened and closed by the turnkey at the cell door. In this form, the end of the lock bolt 20 is attached to a vertical link 80 which extends downwardly through the bottom of the track box, being enclosed by a casing 81. The lower end of the link is connected to a slotted plate 82 which engages a pin 83 on a key controlled lever 84 pivoted in the lower end of the casing. By rotating the lever 84 the lock bolt may be depressed, opening the door when desired. The slot within the plate 82, permits the operation of the lock bolt without, by the levers and flexible connections.

It will be appreciated that while the drawings and description have been detailed in every respect so as to enable those skilled in the art to practise the invention, changes and modifications may be made which do not depart from the scope of the invention as set forth in the claims. Improvements or alterations which fall within the scope of the invention are intended to be covered herein.

What is claimed is:

1. In a jail cell door operating mechanism, a lock for holding the door in closed position, means for securing the door in open position, and a single mechanism for opening the lock to release the door and for actuating the mechanism for securing the door in open position.

2. In a jail cell door operating mechanism, a lock for holding the door in closed position, a detent for holding the door in open position,

and a single control mechanism located at a point remote from the door for releasing the lock and for engaging the door with the detent at its open position.

3. In a jail cell door operating mechanism, the combination of a sliding cell door, a lock for holding the door in closed position, a detent for holding the door in open position, and a single lever mechanism for releasing the lock and for bringing a portion of the door into interlocking engagement with the detent. 75

4. In a jail cell door operating mechanism, the combination of a sliding cell door, a lock for holding the door in closed position, a sliding latch bolt on the door, a detent at the open limit of movement of the door, and means for moving the latch bolt to bring it into engagement with the detent. 80

5. In a jail cell door operating mechanism, the combination of a sliding cell door, a lock for holding the door in closed position, an operating lever connected to the lock, a latch bolt on the door, a bar over which the latch bolt moves, a detent above the bar, and a connection between the lock and the bar by which the latter may be raised to move the latch bolt into engagement with the detent when the door is opened. 85

6. In a jail cell door operating mechanism, a track box above the cell, a pivoted lock for the door located in the track box, a detent in the track box, a movable bar located within the track box, a latch bolt on the door and supported by the bar, and means to release the lock and move the bar when the door is opened so as to bring the latch bolt into engagement with the detent. 90

7. In a jail cell door operating mechanism, a track box above the cell, a pivoted lock for the door located in the track box, a detent in the track box, a bar located in the track box, a detent adjacent the bar, a bolt carried by the door and movable over the bar, a connection between the lock and the bar so that both elements may be moved primarily to release the door and secondarily to bring the bolt in engagement with the detent. 100

8. In a jail cell door operating mechanism, a track box above the cell, and means to secure the door in closed position comprising a lock bolt, and a latch bolt carried by the door, both elements being located within the track box above the cell door. 115

9. In a jail cell door operating mechanism, a track box above the cell, and means to secure the door in closed position comprising a lock bolt, a latch bolt carried by the door, both elements being located within the track box above the cell door, and means connecting the said elements to release them simultaneously. 120

10. In a jail cell door operating mechanism, a track box above the cell, and means to secure the door in closed position comprising a lock bolt, a latch bolt carried by the door, 125

both elements being located within the track box above the cell door, means connecting the said elements to release them simultaneously, and a detent adapted to be brought in engagement with the latch bolt when the door is moved to open position.

11. In a jail cell door operating mechanism, a track above the cell, a door movable along the track, a vertically movable latch bolt on the door, a pull bar with which the latch bolt may be engaged to close the door and hold it in closed position, a bar located above the track, the latch bolt being supported upon the bar, links supporting the bar at either end, and means to rock the links to raise and lower the bar and the latch bolt, the upper surface of the bar being formed on two levels connected by an inclined surface adapted to elevate the latch bolt as the door is brought to closed position.

12. In a jail cell door operating mechanism, a track above the cell, a door movable along the track, a vertically movable latch bolt on the door, a pull bar with which the latch bolt may be engaged to close the door and hold it in closed position, a bar located above the track, the latch bolt being supported upon the bar, links supporting the bar at either end, means to rock the links to raise and lower the bar and the latch bolt, the upper surface of the bar being formed on two levels connected by an inclined surface adapted to elevate the latch bolt as the door is brought to closed position, a lock for the door, a connecting rod extending from the lock to one of said links, and a detent above the bar into which the latch bolt is moved when the bar is elevated.

13. In a jail cell door locking mechanism, a primary locking mechanism comprising a lock bolt adapted to engage a catch at the upper corner of the door and a secondary locking mechanism comprising a latch bolt slidably mounted in the door, a pull bar, a gap nut in the pull bar with which the latch bolt is engaged, and a track box surrounding and enclosing both of said locking mechanisms.

14. In a jail cell door locking mechanism, a track box, a track in said box, a door movable over the track, a plunger adapted to move the door to open position, and a pivoted lock bolt in the track box adapted to engage the door in closed position, a portion of the lock bolt contacting with the plunger and held thereby in unlocked position when the door is opened.

15. In a jail cell locking mechanism, a track box, a track in said box, a door movable over the track, a sliding plunger adapted to move the door to open position, and a pivoted lock bolt in the track box, the head of said bolt adapted to engage the door to hold it in locked position, the tail of said bolt lying over the plunger and held from movement thereby

after the plunger is projected to open the door.

16. In a jail cell locking mechanism, a track box above the cell, a track in said box, a door movable over the track, a catch on the door, a pivoted lock bolt in the track box adapted to engage the catch when the door is closed, a spring to hold the lock bolt in engaged position, and a lever mechanism located outside of the track box and connected with the lock bolt to actuate the latter.

17. In a jail cell locking mechanism, a track box, a track in said box, a door movable over the track, a plate secured to the base of the track box, a lock bolt pivoted in the plate, the head of said bolt engaging the door in closed position, an angularly offset tail on the lock bolt, a door opening plunger mounted in said plate in alignment with the tail, and a head on the plunger movable to a position to prevent pivotal movement of the lock bolt when the door is open.

18. In a cell door operating mechanism, a movable lock bolt for the door, and lever mechanism for operating the same, said parts being movable into three positions, means with which the lock bolt cooperates in the first of said positions for locking the door in closed position, the lock bolt being disengaged from said means for releasing the door when the parts move into the second position, and means for locking the door open, actuated when the said parts are in their third position.

19. In a cell door operating mechanism, a sliding door, a vertically movable latch bolt in the door, means for moving the latch bolt, and a stationary detent above the door into which the latch bolt is movable when the door is opened.

20. In a cell door operating mechanism, a sliding door, a vertically movable latch bolt in the door, means for moving the latch bolt, a stationary detent above the door into which the latch bolt is movable when the door is opened, and a lock bolt for the door movable in unison with the latch bolt.

21. In a cell door operating device, the combination with a pull bar having a recess therein, a bolt carried by the door and movable into and out of the recess, and a mechanically operated device for moving the bolt into engagement with the recess.

HARRY D. GARBER.
